FOOD SERVICE CART

Victor D. Molitor, Englewood, Colo.
(1318 10th St., Denver, Colo.)

Filed Feb. 17, 1958, Ser. No. 49,681

Term of patent 14 years

(Cl. D14—3)

FIG. 1.

FIG. 2.

Fig. 1 is a front perspective view of a food service cart embodying my new design; and

Fig. 2 is a rear perspective view of the food service cart of Fig. 1.

The essential features of my design are shown in full lines.

I claim:

The ornamental design for a food service cart, as shown and described.
